(57) **CLAIM**

The ornamental design for a tray for pipette tips, as shown
and described.

DESCRIPTION

FIG. 1 is a top-front-right perspective view of a tray for
pipette tips, showing my design;

FIG. 2 is a top-front-left perspective view thereof;

FIG. 3 is a top-front perspective view thereof, the top-rear
perspective view being identical thereto;

FIG. 4 is a front elevational view thereof, the rear elevational
view being identical thereto;

FIG. 5 is a bottom plan view thereof; and,

FIG. 6 is a top-front-right exploded perspective view thereof
with a plurality of pipette tips.

The dashed broken lines in FIG. 5 and the dotted broken
lines in FIG. 6 depict portions of the tray for pipette tips that
form no part of the claimed design. The dashed broken lines
in FIG. 6 depict environment and form no part of the claimed
design.

1 Claim, 6 Drawing Sheets
